UNITED STATES PATENT OFFICE.

ALFRED O. YEATMAN, OF WELLINGTON, KANSAS, ASSIGNOR OF ONE-HALF
TO CHARLES E. REED, OF SAME PLACE.

CAR-COUPLING.

SPECIFICATION forming part of Letters Patent No. 361,740, dated April 26, 1887.

Application filed February 18, 1887. Serial No. 238,093. (No model.)

To all whom it may concern:

Be it known that I, ALFRED O. YEATMAN, a citizen of the United States, residing at Wellington, in the county of Sumner and State of 5 Kansas, have invented certain new and useful Improvements in Car-Couplers; and I do hereby declare the following to be a full, clear, and exact description of the invention, such as will enable others skilled in the art to which 10 it appertains to make and use the same.

My invention relates to an improvement in car-couplers; and it consists in the construction and combination of parts, which will be fully hereinafter described, and pointed out 15 in the claims.

The object of my invention is to provide an improved automatic car-coupler, and I obtain this object by the devices illustrated in the accompanying drawings, wherein the same 20 letters of reference indicate the same or similar parts in the two figures, and in which—

Figure 1 is a longitudinal vertical section of my improved coupler, showing the pin in elevated position; and Fig. 2 is a similar view, 25 showing the link coupled in the draw-head.

In the drawings, A represents a draw-head, which is cast in one piece and provided with a rectangular recess, B, running longitudinally therethrough and communicating with 30 a link-opening, B', in the front portion of said draw-head.

B² is a vertical slot formed in the upper portion of the draw-head and adapted to receive and closely fit a coupling-pin, b, which also 35 passes down through the front end of an elongated slot, C, formed in the bottom portion of said draw-head, and having its front wall in direct alignment with the front wall of the vertical slot B', whereby said pin will protrude 40 down through said slots and find a firm support along its front side when the link is coupled thereto.

The slot C is extended backward for some distance from the portion through which the 45 pin b passes, and a pin, c, extends transversely across the same adjacent to its rear wall and is rigidly secured in the sides of the draw-head. This pin is constructed round or cylindrical in shape, for the purpose hereinafter 50 described.

The forward upper half of the draw-head A,

at the front end of recess B, is extended downward for about half the diameter of the recess, as shown at a, thus leaving the front upper portion thereof closed, and causing the link 55 when inserted to enter the lower portion of the recess B.

Situated within the recess B, and adapted to be slid backward and forward, is a bar, D, constructed with a slightly-inclined lower side, 60 and with a lip, d, and an undercut portion, d', at its frontend. A vertical slot, e, is formed in the bar D, and extends forward beyond its center, and in this slot is pivoted, by a screw-bolt, c, the upper end of a pendant, E, which 65 extends downward and through the elongated slot C in the bottom portion of the draw-head, and is provided at its lower end with a weight, e'. This pendant is a rigid straight bar, and has the weight e' secured thereto in any suit- 70 able manner.

To connect the bar D and the pendant E, I form holes across the slotted portion of said bar and through the pendant, and pass the screw-bolt c through the same, thereby securing 75 them together. This screw-bolt forms a pivot, upon which the upper end of the pendant moves, is passed into place through an opening (not shown) in one side of the draw-head, and is removable by ordinary means. 80

Under the construction thus far described, with the bar D, provided with a slanting lower side, and with the vertical slot through the same arranged to extend forward beyond its center, with the weighted pendant attached by 85 its upper end in said slot and in advance of the center of said bar, and with the fulcrum-pin arranged in rear of the pendant, and against which the latter abuts when moved rearwardly with the sliding bar by the coupling-link, it will be obvious that there will be 90 a tendency for said pendant to move away from the fulcrum-pin and assume a vertical position, owing to the weight at its lower end seeking the center of gravity, and that in thus 95 moving forwardly away from said pin it will slide the bar D forwardly in the recess B, where it will normally remain, with its lug d beneath the lower end of the coupling-pin b, and hold the same from dropping down through 100 the front part of the bottom slot, C, until the coupling-link again moves the said bar rear-

wardly. When the link is inserted in the opening B' in the draw-head, it is prevented from coming in contact with the lug d of the bar D by the downwardly-extending or closed portion a, above referred to, and is forced under said closed portion and against the lower undercut portion of said bar, thereby permitting the slotted or open end of the link to pass underneath and beyond the lower end of pin b before the bar is forced back by the link meeting its undercut end, when the pin will be released and drop through the link and the lower slot, and thus couple said link in the draw-head. When the bar D is forced backward by the link the pendant, with the weight at its lower end, is forced into an inclined position, with its weighted end forward and its upper end backward, and a little to the rear of pin c, which acts as a fulcrum, and permits the pendant to move easily or freely thereover. When the link is released by removing the pin the bar D, being then without obstruction at its front end, will be moved forward by the weighted pendant leaving the inclined and assuming the vertical position.

My car-coupler, constructed and operating as described, is cheap, simple, strong, and not liable to get out of order, and hence will be found to possess great advantages over those heretofore employed.

Having thus described my invention, what I claim, and desire to secure by Letters Patent, is—

1. In a car-coupler, the combination of a draw-head, A, having a longitudinal recess,

B, a downward extension, a, a coupling-pin slot, B', in its top portion, and an elongated slot, C, in its bottom portion, with a sliding bar, D, having a lug, d, and a cut-away portion, d', at its front end, a rigid weighted 40 pendant attached thereto, and a coupling-pin, b, adapted to rest upon the front end of said sliding bar, substantially as described.

2. In a car-coupler, the combination of a top and bottom slotted and longitudinally-recessed draw-head, A, provided with the downward extension a and the fulcrum-pin c, the inclined bar D, having the lug d and recess d', the rigid weighted pendant E, attached to said bar forward of its center, and a coupling-pin, 50 b, resting upon the forward end of said bar, substantially as described.

3. In a car-coupler, the combination of a draw-head provided with coupling-pin slot in its top, an elongated bottom slot, a longitudinal recess having a partly-closed end, and a fulcrum-pin with a sliding bar formed with an inclined lower side and with a lug and cut-away portion at its front end, a rigid weighted 60 rod or pendant pivoted to said bar at a point forward of its center, and a coupling-pin resting upon the front end of said bar, substantially as described.

In testimony whereof I affix my signature in presence of two witnesses.

ALFRED O. YEATMAN.
